Primary Examiner — Keith J Wilson*(74) Attorney, Agent, or Firm* — Zarley Law Firm P.L.C.(57) **CLAIM**

The ornamental design for a multi-port dispensing device, as shown and described.

DESCRIPTION

FIG. 1 is a top front right perspective view of a multi-port dispensing device;

FIG. 2 is a front elevation view of a multi-port dispensing device;

FIG. 3 is a rear elevation view of a multi-port dispensing device;

FIG. 4 is right side elevation view of a multi-port dispensing device;

FIG. 5 is left side elevation view of a multi-port dispensing device;

FIG. 6 is top elevation view of a multi-port dispensing device; and,

FIG. 7 is bottom elevation view of a multi-port dispensing device.

The broken lines showing portions of the design in all figures is included for the purpose of illustrating unclaimed features and forms not part of the claimed design.
